[57] CLAIM

The ornamental design for a wood and coal burning stove, as shown.

DESCRIPTION

FIG. 1 is a front perspective view of a wood and coal burning stove, showing our new design with the door in closed condition;

FIG. 2 is a front elevation view thereof;

FIG. 3 is a top plan view thereof;

FIG. 4 is a left side elevation view thereof;

FIG. 5 is a right side elevation view thereof;

FIG. 6 is a rear elevation view thereof;

FIG. 7 is a bottom plan view thereof; and

FIG. 8 is a front elevation view thereof with the door removed.
